UNITED STATES PATENT OFFICE.

PAUL W. FLEISCHER, OF NEW YORK, N. Y., ASSIGNOR TO AMERICAN CAN COMPANY, A CORPORATION OF NEW JERSEY.

CAN-CLOSING MACHINE.

1,330,071.

Specification of Letters Patent. Patented Feb. 10, 1920.

Original application filed December 1, 1915, Serial No. 64,494. Divided and this application filed December 6, 1915. Serial No. 65,246.

To all whom it may concern:

Be it known that I, PAUL W. FLEISCHER, a citizen of the United States, residing in New York, in the county of New York and 5 State of New York, have invented a new and useful Improvement in Can-Closing Machines, of which the following is a specification.

The invention relates to can closing machines, and has for its object to enable these machines to be operated successfully by persons who are not skilled, or who are occasionally careless, by automatically preventing the breakage of or injury to those parts 10 of the machine, and their actuating connections, which feed the can ends. It is desired to drive these machines with high power and at comparatively fast speed, and in case a can end which enters the machine is, through 15 accident or carelessness, not of the size or formation on which the machine has been adjusted to operate, or in case such can end is not properly positioned by reason of an unskilful or hasty adjustment of some part 20 of the machine, the mechanism may become jammed and the machine stopped against the full power of the prime motor. The result of this condition is or may be quite serious, requiring the operation of packing 25 (can closing) to be suspended, with loss of time and material, until a broken or injured essential part of the mechanism can be replaced or repaired.

According to the present improvement the 30 machine is made to a material extent automatically proof against such accidents by providing the can end feeding mechanism with a yielding friction driver which overcomes all of the resistance due to the ordinary and desired operation of said feeding 35 mechanism, but which will yield in the case of unusual obstruction or resistance and allow the can end feed devices to come safely to rest, while the prime motor, and main 40 power shaft or elements of the machine driven thereby, may continue to operate until the power is disconnected. A deformed or obstructing can end may then be removed, the adjustment of the machine perfected if 45 necessary, and the packing operation can be continued with the minimum loss of time.

There are advantages in applying such an automatically releasing drive element to the cam shaft which actuates most of the sub-

mechanisms of the machine, but whether or 55 not that be done it is a material advantage and improvement to apply such a yieldable driver directly to or in the can end feed mechanism. This mechanism is rather complicated and delicate, especially when it 60 comprises means whereby it is controlled by the can which is to be closed; and when the said releasing drive element is applied to the cam shaft it must be constructed to transmit very considerable power before it will yield, 65 and it cannot readily be made to yield by an obstruction in the comparatively weak and delicate can end feed mechanism.

With such objects in view, as well as the 70 attainment of all other features of usefulness and advantage which are inherent in the improved can closing machine, the invention consists in the parts and combinations thereof hereinafter set forth and claimed.

In order to make the invention more 75 clearly understood there are shown in the accompanying drawings means for carrying the same into practical effect, without limiting the improvements, in their useful applications, to the particular construction, which, for the purpose of example, has been made the subject of illustration. In the said drawings:

Figure 1 is a front elevation, partly in section on line I—I of Fig. 2 on the vertical plane of the seaming head axis, of a portion 80 of a can closing machine embodying the invention.

Fig. 2 is a plan view of the feed table 85 below the seaming head.

Fig. 3 is a perspective view of a part of the can control device,

Fig. 4 is a vertical cross section on line 90 IV—IV of Fig. 5.

Fig. 4^a is a section on a larger scale on line 95 IV^a—IV^a of Fig. 4.

Fig. 5 is a plan view of the parts shown in Fig. 4.

Fig. 5^a is a section on a larger scale on 100 line V^a—V^a of Fig. 5.

Fig. 6 is an elevation looking from the rear of the machine, showing the yieldable driver or power connection for the can end feed mechanism.

Fig. 7 is an elevation of a portion of the machine looking in the direction of the can end feed illustrating the vertical adjust-

75

85

105

ability of the seaming head casing and can end feed bracket.

Referring to the drawings:—from which most of the frame parts have been omitted 5 for clearer illustration, 87 is the seaming head under which the filled and open top cans are fed by a continuously moving chain 52. 84 is a lifter which successively raises the cans through a centering device 252 to 10 receive a can end over its top and be presented to the seaming head. 257 is a slide which delivers the can ends from under a stack holder 254 over the said centering device. 59 is a main vertical cam shaft which 15 drives the feed chain sprocket 50 by a chain 57, the lifter by a cam and yoke lever, and the slide 257 by an eccentric 348. 143 is a vertical hollow shaft which rotates the seaming head and parallel with which the 20 latter is vertically adjustable. The shafts 59 and 143 may be driven by any appropriate mechanism.

The frame 1 of the machine, extends upwardly and has vertically slidably mounted 25 upon the front face thereof a seaming head casing 131. This casing overhangs the table 21 and is provided with vertical flanges 132 adjacent the frame 1 which are retained against the same by vertical guide members 30 133 adjustably secured to the frame 1 by lock bolts 134, which normally bind the casing 131 against the frame 1 and hold the same securely against vertical displacement. Secured to the top of the casing 131 is a vertical 35 adjusting non-rotary shaft 135 which extends upwardly along the face of the frame 1 and is supported at its upper end by the hub of an adjusting hand wheel 136 which is threaded onto the said shaft and 40 rests upon a bifurcated and outwardly projecting supporting lug 137. When it becomes necessary to raise or lower the seaming head to accommodate cans of a different size (height), the locking bolts 134 are 45 loosened permitting the casing 131 to be raised or lowered as the case may be by the hand adjusting wheel 136 carrying with it the seaming head and its actuating gearing.

Secured at one end to the under side of 50 the seaming head casing 131 and extending outwardly therefrom and overhanging the main conveying table 21 of the machine, is a can end feed bracket 250. This bracket has a channel or track 251 machined in its 55 upper face which corresponds in shape in cross section to the cross section of a can end so that the top surface of a can end being conveyed along the said track will be flush with the surface of the bracket 250. 60 The track 251 extends inwardly and terminates in a circular aperture 252 in the bracket 250 axially beneath the seaming head 87 and over the can lifter 84. The can end is deposited over this aperture by a 65 feeding mechanism presently to be de-

scribed, and there awaits the can body as it rises under the action of the can lifter 84, being of a larger diameter before seaming than the said aperture. Said aperture 70 forms a centering device for the can as it is elevated to the seaming head, being flared or beveled at the under side of the bracket, as shown at 252' (Fig. 1). Secured to the bracket 250 and above the track 251 is a casing or cover 253, which forms the support 75 for a can end stack holder 254, the latter being located above the outermost end of the track or channel 251. The casing 253, beneath the can end holder 254, has a circular aperture 254' therein to permit the can ends to descend vertically from the holder 254 to the track 251 and into position to have the lowermost one separated 80 from the stack and conveyed along the said track to the marking device which will be described later. In the bracket 250 and substantially in the center of the track 251 is a longitudinal slot or passageway 255 which extends down through the bracket and the sides of which are horizontally recessed as 90 at 256 and form the supporting and guiding means for a reciprocating slide 257, the sides of which are so shaped as to engage within the horizontal recesses 256. The slide 257 is preferably formed in two parts, 95 a lower and longer finger bar 258 and an upper and shorter carrier bar 259. Pivoted to the inner extremity of the finger bar 258 is a can end engaging finger 260 which extends upwardly above the surface of the track 251 and in the path of the can ends. This finger is normally held in its upward and engaging position by a leaf spring 261 which bears against an outwardly projecting lug 262 on the finger 260. The inner 100 and can end engaging shoulder 264 of the carrier bar is provided with a steel fin 265 which extends inwardly slightly and projects over the can end when the latter is engaged and serves to some extent to assist 105 in separating the lowermost one of the nested can ends from the stack prior to extracting it from beneath the stack and conveying it to the marking device.

Mounted upon the bracket 250 upon an 115 eccentric adjusting pivot 266 and located at one side of the passageway 255, is a lever 267 one end of which carries a can end separating knife 268 while the other end thereof carries a roller 269 which bears against 120 the edge of the carrier bar 259, and coacts with a recess 270, in the form of a cam or inclined surface 271, in the latter. The roller 269 is yieldably held against the side of the carrier bar 259 by a spring 272, one 125 end of which is attached to the inner end of the lever 267 and the other end thereof secured to the bracket 250. It will be seen that when the slide 257 is moved to its outermost position the roller 269 under the action 130

of the spring 272 will engage in the recess 270 in the carrier bar 259, allowing the separating knife 258 to move laterally from beneath the stack of nested can ends and permitting the same to descend and rest upon the track 251. When, however, the slide 257 commences to move inwardly along its guideway, the cam surface 271 will engage the roller 269 and force the same out of the recess 270 until it bears against the straight side of the carrier bar 259. This outward movement of the roller 269 overcomes the spring 272 and turns the lever 267 about its pivot, causing the separating knife 268 to enter between the edges of the can ends in the stack and above the bottom one, cutting out the latter from its nested position and at the same time lifting the remainder of the stack and supporting the same clear of the carrier bar 259 as it conveys a single can end so separated along the track to the marking device. Located in the bracket 250 and at a point midway between the can end feeding and seaming stations, and extending 25 at right angles to the track 251, is or may be a can end marking device denoted as a whole by the numeral 273.

Secured to the under side of the seaming head casing 131 and extending outwardly therefrom is a can end feed lever bracket 324 terminating in a vertical bearing 325. Suspended beneath this bearing is a can end feed lever 326 which is supported by a stud shaft 327 which is integral therewith and which extends upwardly and is journaled in the said bearing 325 (Fig. 4). The can end feed lever 326 is preferably of inverted channel bar form and forms a housing 328 for a can end feed lever arm 329. This arm 329 is pivoted as indicated at 330 between the flanges of the housing 328. The lever arm 329 is normally held in a raised position by a coiled spring 331 located near the inner or rear end of the lever arm. The upward movement of the outer extremity of the said lever arm 329 is regulated by a set screw 332 in the lever arm housing 328. The said lever arm 329 extends outwardly and beneath the can end feed bracket 250 and feed slide, engaging two pins 333 and 334 (Figs. 4 and 5) located on the under side of the finger bar 258 and which project downwardly therefrom upon each side of the lever arm 329. The forward pin 334 is slightly shorter than the rear pin 333 and is beveled as indicated at 335. It will be apparent that when the lever arm 329 moves forward toward the seaming station it will engage the shorter pin 334 thereby causing the slide 257 to move forward, and upon the backward movement of the said arm 329 the same will engage the longer pin 333 and cause the slide 257 to move rearwardly and into position to extract another can end from beneath the stack.

It will be apparent that as the slide 257 is reciprocated the shoulder 264 of the carrier bar 259 will extract the separated can end from beneath the stack and convey it along the track 251 to the marker 273, where 70 it is deposited and left between the stamping dies of the same. The slide then returns and upon its next forward stroke the finger 75 bar 260 of the finger bar 258 will remove the can end previously deposited in the marker 75 and stamped, from the said marker and carry it to the centering device where it is deposited over the aperture 252 and in position to be engaged by a can body and seamed thereon. While the finger bar 258 has been 80 removing the stamped can end from the marker to the seaming head, the carrier bar 259 has extracted another can end from beneath the stack and deposited it in the marker where it has been stamped and is 85 waiting to be delivered to the seaming head by the finger bar. By this method there is a constant and successive feeding of marked can ends to the seaming station without the loss of time. 90

In order to prevent the can end from riding backward out of the marker, upon the carrier bar 258 on the backward stroke of the same and after the can end has once been deposited there by the said carrier bar 259, 95 there is provided in the casing 253 and adjacent the marker 273 a pin 336. This pin projects downwardly through the casing 253 and has its lower end beveled as at 337. The upper end of the pin 336 engages a leaf 100 spring 338 (Fig. 1) which serves to yieldably hold the said pin in its downward and can end engaging position. While a can end is conveyed into the marker by the carrier bar 259 it engages the beveled surface 337 105 of the pin 336 forcing the latter upward and allowing the can end to pass beneath. But upon the rearward stroke of the carrier bar the can end engages the straight edge of the pin 336 and is thus prevented from moving 110 rearwardly out of the marker.

The wearing surfaces of the bearing 325 are protected by a tubular bushing 339 having at its upper extremity a collar 340 which forms a bearing surface for a lever latch arm 341 which is mounted upon the upper end of the stud shaft 327. The lever 326 and its shaft 327 are supported in the bearing 325 by a washer 342, which is secured by a screw 343 to the upper end of the stud 115 shaft 327 and rests upon the latch arm 341. Pivoted to the outer end of the said latch arm 341 by a pivot pin 344 is an eccentric rod connection 345 into which is threaded an eccentric rod 346. The said eccentric rod 120 extends across the machine and is secured to an eccentric strap 347 which passes around an eccentric 348 fixed upon the vertical cam shaft 59. Beneath the latch arm 341 and preferably integral therewith is a down- 130

wardly extending web or flange 349 which terminates in a latch housing 350. Vertically slidably mounted within the said housing 350 is a latch block 351 of hardened steel 5 having its lower face beveled at an angle of about 45° as indicated at 352. Integral with the top of said latch 351 is a latch rod 353 which extends vertically through an aperture in the latch arm 341. Encircling 10 the latch rod 353, and confined between the arm 343 and an adjusting nut 354 on the said latch rod is a compression spring 355 which has a tendency to normally yieldably hold the latch 351 in engagement with a recess 356 designed to receive it in a plate 357 of hardened steel secured to the lever arm 326. The upper end of the latch rod 353 is notched as at 358 to receive the edge of a latch stop 359 pivoted on the upper side of 15 the latch arm 341. When the latch 351 is normally in engagement with the recess 356, the said notch 358 is below the surface of the latch arm 341 and out of engagement with the latch stop 359. It will be apparent 20 that under the normal strain of operating the machine the pressure of the spring 355 will suffice to keep the latch 351 in engagement with the recess 356, and in consequence the latch arm 341 and the lever arm 329 will 25 be oscillated as a unit by the eccentric 348. But should anything break or become clogged or jammed in the mechanism of the machine the unusual strain caused thereby will cause the latch 351 to be forced out of 30 its engaging recess 356, at the same time raising the latch rod 353 enough to bring the notch 358 into alignment with the latch stop 359, which will instantly, under the pressure of a leaf spring 360 engage the said 35 notch, preventing the latch 351 from again registering with its recess 356, from which it results that the eccentric 348 will oscillate only the latch arm 341 without operating 40 the lever arm 329. This will continue until the obstruction in the machine is removed 45 or the power turned off. When it is desired to again operate the machine, the stop 359 is released, allowing the latch under the action of the spring 355 to return to its normal 50 engagement with the recess 356, causing the disconnected parts to again oscillate as a unit and operating the slide 257.

Pivoted to the under side of the bracket 324 is a can end feed index lever 361 (Fig. 5) having a long arm 362 and a short arm 363 extending at substantially right angles to each other. The arm 362 extends outwardly and over the lever arm housing 328 and is provided on its under side and at 55 its outer end with a cam 364. This cam engages a pin 365 projecting vertically from the lever arm 329 through an aperture 366 in the lever arm housing 328 and tends to normally depress the outer end of the said 60 lever arm and hold the same out of engage- 65

ment with the forward and shorter pin 334 in the finger bar 258. Secured to the arm 363 of the said index lever 361 is a connecting rod 367 which extends across the machine beneath the seaming head casing 131, 70 and which is held up in a horizontal position by a guiding support 367' attached to said casing.

Mounted upon the table near the receiving end thereof and adjacent the path of the cans passing to the seaming station is a bracket 368 in which is mounted a vertical stud shaft 369, which is integral with a can-controlled trip lever 370 which rests upon the table 21 and which projects across 80 the path of the cans beneath the can guides and which is actuated by the passing cans. Adjustably mounted by means of a clamp bolt 371 upon the stud shaft 369 and below the bracket 368 is a vertical lever arm 372 85 which engages a notch 373 in an arm connection 374 to which is secured the end of the connecting rod 367. It will be apparent that through this construction the lever arm 329 will normally oscillate to and fro without 90 reciprocating the slide 257, but as soon as a can body passing along its track engages the trip lever 370, it will force the same inward (Fig. 2) thereby throwing the vertical lever 372 about its pivot, causing the 95 arm 362 of the cam lever 361, through the medium of the connecting rod 367, to be moved from its engaging position above the pin 365 in the can and feed arm 320 (Fig. 5) allowing the same to rise under the action of the coiled spring 331 to its engaging position with the short pin 334 in the finger bar 258, which can then be moved forward by the arm 329. When the arm reaches a point near the limit of its throw, 105 the housing 328 will engage a set screw 375 mounted in a downward projecting lug 376 on the under side of the can end feed lever 361, causing the latter to be rotated about its pivot and causing the longer arm 362 thereof to again be moved back to its normal position over the path of the pin 365. Now when the can end feed lever arm 329 returns on its backward movement the pin 365 will engage under the cam 364 on the 110 lever arm 362 causing the lever arm 329 to be depressed out of engagement with the shorter pin 334 on the finger bar 258. The arm will continue to oscillate about its pivot (supposing the feeding of cans to be interrupted) being depressed each time when it reaches a point near the limit of its backward movement. This will continue without any actuation of the can end feed slide until another can actuates the can-controlled 115 trip lever 370 causing the arm 362 and its cam 364 to be thrown out of the path of the pin 365. It will be noticed that the lever arm 329 is not depressed low enough 120 to prevent it from engaging the longer pin 125 130

333 on the finger bar 258, which pin is only encountered by the lever arm 329 on its return or backward movement and which is designed only to return the slide 257 to its outward position. It will also be noticed that the can end feed mechanism is thrown into operation by each individual can as it actuates the can-controlled lever and is thrown out of engagement as soon as a can 10 end is fed to the seaming station; and if a can body is not in position to be closed a can end will not be fed to the seaming station.

By "seaming head" I include various can 15 end attaching means. Such means may be a clencher which crimps the head loosely on to a can, all around the circumference or in spots. Also, when the seaming head is used, only the first operation or curling 20 roll may be put in operation, the complete hermetic seaming by the second operation being done by any suitable means after processing the filled and partly or loosely closed can; and the words "closing machine" are 25 not limited to a machine which hermetically closes the cans.

This application is a division of my co-pending application Serial No. 64,494, filed Dec. 1, 1915.

30 What is claimed is:—

1. In a can closing machine, adapted to unite can ends to can bodies by an inter-folded seam or joint, comprising a seaming head; a centering and rounding up member; 35 a track along which cans are moved; a can end feed station and feed mechanism; means for operating the feed mechanism; a movable can end feed controlling member normally protruding into the path along which cans 40 are moved; a connection between said feed controlling member and said can end feed mechanism whereby said feed mechanism operates to feed a can end each time said controlling member is moved by an advancing 45 can, and means on said operating mechanism for resetting said controlling member to again intercept the cans as they are moved along the said path.

2. In a can closing machine in combination; a can conveyer, a can end feeding mechanism, means for operating the feeding mechanism, a can end feed controlling arm intercepting the path of the cans; a connection between the said arm and feed mechanism whereby as the arm is moved by an advancing can, the feed mechanism operates to feed a can end, means connected with the operating means which at the same time restores the said arm to its normal position in 60 the path of the cans.

3. In a can closing machine, in combination: a can end feeding mechanism comprising a track and slide; a transverse vertically movable pivoted lever engageable with said 65 slide; a horizontally movable lever in which

is mounted the pivot of the slide-engaging lever; means for actuating the horizontally movable lever; and can controlled means for moving the slide-engaging lever vertically.

4. In a can closing machine, in combination: a can conveyer; a can controlled arm in the path of the cans; a can end feeding mechanism; a connection from the said arm to the can end feed mechanism having means for throwing the latter into operation; and means whereby the can end feeding movement of the said mechanism restores the said arm into the path of the cans. 70

5. In a can closing machine, in combination: a can conveyer; a can controlled arm 80 in the path of the cans; a can end feeding mechanism; means for adjusting said can end feeding mechanism vertically relative to said conveyer; and a connection from the can end feed mechanism to said can controlled arm having means whereby it may be vertically adjusted while still connected with said arm, said connection having means for throwing into operation the can end feed mechanism. 85

6. In a can closing machine, in combination: a seaming head; a bottom plunger co-operating therewith; a can centering device interposed between the said seaming head and bottom plunger; a can end track leading to said centering device; can end feed mechanism arranged to deliver can ends along said track to said centering device; and a frictional yieldable latch for actuating said can end feed mechanism. 90

7. In a can closing machine, in combination: a seaming head; a bottom plunger co-operating therewith; a can centering device interposed between the said seaming head and bottom plunger; a can end track leading to said centering device; can end feed mechanism arranged to deliver can ends along said track to said centering device; and a frictional yieldable latch for actuating said can end feed mechanism, comprising a 100 friction, spring-actuated latch-bolt and notch separably connecting said levers. 105

8. In a can closing machine, in combination: a seaming head; a bottom plunger co-operating therewith; a can centering device 115 interposed between the said seaming head and bottom plunger; a can end track leading to said centering device; can end feed mechanism arranged to deliver can ends along said track to said centering device; and a frictional yieldable latch for actuating said can end feed mechanism, comprising two levers connected respectively with the power mechanism and with the can end feed mechanism, and a friction spring-actuated 120 latch-bolt and notch separably connecting said levers. 125

9. In a can closing machine, in combination: a seaming head; a bottom plunger co-operating therewith; a can centering device 130

- interposed between the said seaming head and bottom plunger; a can end track leading to said centering device; can end feed mechanism arranged to deliver can ends along said track to said centering device; and a frictional yieldable latch for actuating said can end feed mechanism, comprising a friction, spring-actuated latch-bolt and notch separably connecting said levers; and automatically acting means for keeping said latch-bolt out of engagement when it has been forced out of its notch.
10. In a can closing machine, in combination: a can end feeding mechanism comprising a slide; a transverse vertically movable pivoted lever engageable with said slide; a horizontally movable lever in which is mounted the pivot of the slide-engaging lever and formed of two parts; a yielding friction connection uniting the said two parts of the lever; means for actuating said horizontally movable lever; and can controlled means for moving the slide-engaging lever vertically.
15. 11. In a can closing machine, in combination: a can end feeding mechanism comprising a slide; a transverse vertically movable pivoted lever engageable with said slide; a horizontally movable lever in which is mounted the pivot of the slide-engaging lever and formed of two parts; a friction spring-actuated latch-bolt and notch separably connecting the said two parts of the lever; means for actuating said horizontally movable lever; and can controlled means for moving the slide-engaging lever vertically.
20. 12. In a can closing machine adapted to unite can ends to can bodies by an interfolded seam or joint; comprising a seaming head, a track along which cans are moved to an assembling station; a separate track along which can ends are moved to the same assembling station; a can end feed station and feeding mechanism; means for operating the feed mechanism; a can end feed controlling member normally projecting into the line of travel of the cans on said track; a connection between said feed controlling member and said can end feed mechanism whereby said feed mechanism operates to feed a can end each time said controlling member is moved by an advancing can and means on said operating mech-
- anism for resetting said controlling member to again intercept the cans as they are moved along said track to said assembling station; and a member at said assembling station for receiving can ends as fed and for rounding up and alining can bodies as they are assembled with can ends preparatory to uniting the said ends to the said bodies by an interfolded joint or seam.
13. In a can closing machine, in combination: a seaming head; a can end feeding track leading to a point under said seaming head; a slide in said track; a two-part lever for actuating said slide; a can end stack; a laterally operating separating knife adapted to enter said stack and operated by said slide; a frictional yieldable latch connecting the two parts of said lever; and means for actuating said lever.
14. In a can closing machine, in combination: a seaming head; a can end feeding track leading to a point under said seaming head; a slide reciprocable in said track; a three-part lever for yieldingly actuating said slide; said lever comprising a horizontally oscillating member, a vertically oscillating slide-actuating member pivoted thereon, and a horizontally oscillating latch arm member adapted to yieldably engage said horizontally oscillating member; and means for normally actuating the three parts of the said lever in unison.
15. In a can closing machine, in combination: a can end guiding track; a slide for propelling the can ends; a lever having a separable engagement therewith; means for actuating said lever comprising a yieldable power-transmitting latch; a second lever which controls the engagement of said first lever with the slide; and means whereby a can to be closed actuates said second lever.
16. In a can closing machine, in combination: a seaming head; a can end feeding track leading to a point under said seaming head; a slide in said track; a lever operative along and toward said slide for actuating the same; a can end stack; a beveled projection on the slide engageable by the lever for actuating the slide and for deflecting the lever; and means for actuating said lever.

In testimony whereof I have affixed my signature hereto.

PAUL W. FLEISCHER.
